INVENTOR
EUGENE L. BARNES

By ATTORNEY

UNITED STATES PATENT OFFICE

EUGENE L. BARNES, OF BUFFALO, NEW YORK

EVAPORATING UNIT

Application filed March 28, 1931. Serial No. 525,945.

My invention relates in general to evaporating units, and in particular to such units as are used in refrigerating systems of the household type.

It is well known to those skilled in the art that at present considerable difficulty is experienced in keeping the lubricant in refrigerating systems in circulation in the evaporating unit. This is so because there is little tendency of the refrigerant to circulate in such units, particularly when there is a difference in specific gravity between the refrigerant and the lubricant. When the specific gravity of the refrigerant is even slightly less than the lubricant, the lubricant has a tendency to settle to the bottom, resulting in a consequent decrease in the efficiency of the unit.

The principal object of my invention has been to provide a refrigerating unit in which there shall be a positive circulation of the refrigerant contained therein.

Another object has been to provide a refrigerating unit which shall give maximum exposed area for any given cubical space occupied by the unit.

Moreover, it has been an object to provide an evaporator unit, all the walls of which, except those at the end, shall be made of a single piece of sheet material.

Furthermore, my device is simple and inexpensive to manufacture, and very durable in construction.

The above objects and advantages have been accomplished by the device shown in the accompanying drawings, of which:

Fig. 1 is an end view of a preferred form of my invention.

Fig. 2 is a fragmentary, side elevation thereof, portions thereof being in section, and taken on line 2—2 of Fig. 1.

Fig. 3 is a fragmentary, sectional view through the walls of the ice tray compartment and is taken on line 3—3 of Fig. 1.

Fig. 4 is an enlarged, fragmentary, sectional view showing the joint in the ice tray compartment, and is taken on line 4—4 of Fig. 2.

Fig. 5 is a similar view taken on line 5—5 of Fig. 2.

Fig. 6 is a fragmentary, end elevation of a detailed modification of the invention shown in Fig. 1.

Fig. 7 is a fragmentary, end elevation of my device constructed in a modified way. 55

Fig. 8 is an enlarged, fragmentary, sectional view taken on line 8—8 of Fig. 9.

Fig. 9 is an enlarged, fragmentary, sectional view, taken on line 9—9 of Fig. 8.

Fig. 10 is a fragmentary view of another modified form of invention.

Fig. 11 is a fragmentary, side elevation of the form of device shown in Fig. 10.

Fig. 12 is a modified form of invention showing a specific type of ice tray support. 65

My device comprises in general a pair of adjacent refrigerant chambers having their axes in a substantially horizontal plane and being connected near their tops and bottoms by means of passageways. The liquid refrigerant coming from the condenser is delivered into one of the chambers of the device, and the vapor refrigerant which is taken off from the device by the compressor is drawn from the other chamber, whereby circulation 70 of fluid occurs between the chambers. 75

Referring particularly to the form of invention shown in Figs. 1 to 5, inclusive, 10 represents the inlet chamber, and 11 the outlet chamber. These chambers are arranged 80 adjacent to each other and have their axes in a substantially horizontal plane. The chambers 10 and 11 are connected near their tops preferably by means of a vapor pipe 12, whereby the vapor in the chambers will have 85 free passage from one chamber to another and will thus be substantially balanced in pressure. In order to have an equilibrium in the refrigerant chambers 10 and 11, it is necessary that these chambers be also connected near their bottoms. This may be accomplished in any one of a number of well known ways, either by means of coils, passageways, or interspaced plates. In the form 90 of invention shown in the figures just considered, passageways are formed in the walls of the ice tray compartment 15. These walls are preferably formed of two layers 16 and 17 of sheet metal which are disposed in intimate contact with each other, passageways 18 be- 100

ing formed in the sheet 16 by forcing the metal into outwardly extending ridges 19, the adjacent layer or plate serving to close the open sides of the channels formed by such ridges.

I found it convenient and advantageous to form not only the two chambers 10 and 11, but also the ice tray compartment, of a single sheet of material. As shown in these figures 10 one end of the sheet is indicated at 20 and the other end thereof at 21. The sheet, starting with the end 20 is extended across the bottom 22 of the ice tray compartment 15, starting at substantially the middle thereof, 15 extending up the side wall 23 with its obliquely formed portion 24 and then being fashioned circularly so as to form the side walls 26 of the refrigerant chamber 10. After the sheet is extended around the circle forming 20 this wall, it is brought in contact with the layer 16 at the point indicated at 27 where the joint is preferably welded so as to make a completely liquid-tight side wall. From this point the sheet is extended in the layer 25 identified by the numeral 17 downwardly along the side wall 23 with its oblique portion 24 and in intimate contact with the layer 16 of such side wall. It is extended across the bottom 22 and up the opposite side wall 30 28 with its oblique portion 29 of the ice tray compartment. When this part of the sheet reaches the point 30, it is then fashioned like the cylinder 10 into side wall 31 of the refrigerant cylinder 11. When the material 35 has been formed into this circular side wall and is brought again to the point 30, it will then be extended in the layer 16 down the side wall 28 and its oblique portion 29 and across the bottom 22 terminating in end 21 40 of the sheet. The end 21 is offset the thickness of the material so as to lie flatly against the end 20, as clearly shown in Figs. 1, 4 and 5. The joint thus formed is suitably welded so as to make the walls of the ice tray compartment 45 tight. The ridges 19 are, of course, formed only on that portion of the sheet which is indicated as layer 16, such ridges terminating at the points where the layers of the sheet forming the side wall join with 50 the portions thereof which form the refrigerant chambers. The upper ends of these ridges are cut off substantially at right angles and are joined to the side walls 26 and 31 of the refrigerant chambers 11 and 10, respectively. 55 These ends are welded to the side walls so as to make a tight joint and openings 35 (as shown in Fig. 2) are formed in the said side walls so as to connect the interior of the chambers with the passageways 60 18 formed in the walls of the ice tray compartment. It will be clear from the above description that the refrigerant chambers 10 and 11 are connected together near their lower portions by means of the passageways 18. 65 It is preferable to form at some point in the

bottom wall 22 a longitudinal header passageway 36 opening into the passageways 18 at each side of the unit, as clearly shown in Figs. 2, 4 and 5. Where the ends 20 and 21 overlap, the material forming the portions 70 of the sheet 16 lying between the corrugations at such ends is not brought up to and in contact with the surface of the other layer 17, but is depressed, as shown in Figs. 2, 4 and 5, for some distance back, thus terminating the passageways 18 short of the ends 20 and 21, whereby the longitudinal passageway 36 is formed.

Where it is desired to obviate the necessity of terminating the upper edges of the 80 ridges and welding them to the side walls of the refrigerant chambers, the form of invention shown in Fig. 6 may be used. As here shown, a relatively large curved portion 40 is formed at the end of each of the ridges 19 85 where the ridge joins the side wall 26 of the chamber and these portions are formed at the time the ridges are formed.

Fitted into the front ends of the chambers 10 and 11 are end heads 41 and 42, respectively, which are welded in place so as to make the chambers leak-proof. Suitable heads 43 are also secured into the rear ends of the chambers 10 and 11 to which the gas pipe 12 is attached. These heads are, of 95 course, welded in place in a leak-proof manner. The ice tray compartment 15 is closed at its rear end preferably by means of a wall 44.

Carried by the front head 41 of the refrigerant chamber 10 is the liquid inlet fitting 45, and carried by the end head 42 of the refrigerant chamber 11 is the vapor outlet fitting 46. Each of these fittings may be any one of a number of standard types and 100 does not form a part of my invention. They will not, therefore, be described in detail. Carried by the lubricant chamber 10 is the usual float 47 which is connected in the customary manner with the liquid inlet fitting 45 so as to maintain a level of liquid within the chambers 10 and 11.

Reference is now to be had to the invention shown in Figs. 7 to 9, where for clearness of illustration only one of the refrigerant chambers 50 is shown. The device is, however, constructed, as in the form of invention just described, of a single sheet of material, and it is designed to obviate the tendency of the ridges in the form shown in Fig. 1 to flatten at the corners of the ice tray compartment or at any other place where bends in the material are to be formed. In this form wherever a bend is to be provided, the ridges terminate and are continued in a formation of a ridge in the opposite layer of the sheet. Thus in this form the sheet is continued across the bottom 51 of the ice compartment from the end 52 in a flat condition. 125 When the corner 53 is reached where a right 130

angled bend is to be formed, the flat material is bent at right angles, and ridges 54 are formed in the side wall 55 and extend outwardly on the surface thereof from the corner 53 until the corner 56 is reached. The ridges terminate at the angle 56 and the material is then bent at the desired angle and from this point on until the place where the chamber is to be formed is reached this layer 57 of material is flat. The side wall 58 of the chamber 50 is thereafter formed, and it is welded at point 59 where it joins the layer 57 as in the other form of invention. The ridges 60, however, in this portion of the wall 15 extending from the side wall of the refrigerant chamber 50 to the upper end of the side wall 55 are formed in the layer 61. At a point opposite the ridges 60, the wall 58 of the chamber is formed with openings similar to the openings 35 of the form of Fig. 2. The point in the layer 61 at the upper end of the side wall where the ridges 60 are attached is also provided with openings so that the passageways formed in the ridges 57 may 20 have communication with the passageways formed by the ridges 60 in the manner shown in Figs. 8 and 9, which will now be described. The layer 61 is continued down the side wall 55 in contact with the layer 57 and it is bent 25 at right angles at the point 53 and extended across the bottom 51 of the ice compartment on top of the layer 57. The ridges 62 across the bottom of the ice tray compartment are formed in the layer 61 and these ridges terminate at the point where the bend 53 is 30 formed. The end face of the ridge is in contact with the layer 61 of the side wall as clearly shown in Fig. 8 and this end is welded to such layer so as to completely seal the 35 passageway. An opening 65 is formed in the layer 61 of the side wall at the bottom thereof (see Figs. 8 and 9) and in registering position with the passageway of the ridges 62, whereby there is communication between 40 the passageways of the bottom 51 and side walls 55 of the device. Obviously, the material is continued from the point where it is broken off, for clearness of illustration, and the opposite refrigerant chamber and side 45 wall formed from the same piece of material, as hereinbefore described in connection with the form of Fig. 1.

In Figs. 10 and 11 I show a form of invention in which the passageway connecting the bottoms of the refrigerant chambers are formed by the two interspaced layers 66 and 67. So as to strengthen the unit and to increase the radiating surface thereof, the walls 66 and 67 are formed in serpentine fashion by 50 means of the corrugations 71, a spacer 68 being provided at each end of the chamber and at as many intermediate points as is deemed necessary to keep the layers properly separated. Where the separator is located at the 55 edges of the layers, it is obvious that the

joints will be welded so as to make the device leak-proof. A passageway 69 is thus provided between the interspaced layers for permitting communication between the two chambers. As in the other modification of Fig. 7 only one refrigerant chamber 70 is shown, but it is clear that two chambers are also provided in this form and that both chambers as well as the ice tray compartment may be formed from a single sheet of material. 75

Where it is desired to form a partition for holding a plurality of ice trays, the form of invention shown in Fig. 12 is used. As here shown, a shelf or partition 72 extends inwardly toward the center of the ice tray compartment 73 for accommodating at one side of the compartment two ice trays 74 and 75. Where such a shelf or partition is formed at only one side of the compartment, an ice tray 76 of maximum height may be used at the opposite side. The shelf or partition 73 is preferably of such length that it engages with the side wall of the tray 76 and acts as a stop or separator therefor. In the formation of a device having the partition or shelf 72, and made from a single piece of material, the inner layer 77 of the material is extended inwardly at the point where the shelf is to be formed and then returned upon itself, 80 continuing up the side wall as clearly shown in this figure, the joint between the material at the point 78 being welded so as to prevent the liquid refrigerant from getting in between the layers of the material forming the shelf. The refrigerant chambers 79 and 80 as well as the ridges 81 are formed as described in connection with the form of invention shown in Fig. 1. It is obvious, however, that this shelf or support may be 85 formed on either of the forms of invention shown in the other figures of the drawings. 100

I have referred to the welding of the joint in the form of invention shown in Figs. 10 and 11 at the edges of the ice tray compartment and it is obvious that in the other forms of invention where the layers of material come together at the edges, they are suitably welded so as to make the entire device leak-proof. The walls of the ice tray compartment are also preferably spot welded at suitable intervals so as to properly strengthen the structure. 115

While I have shown the liquid inlet fitting 45 and the vapor outlet fitting 46 in a conventional manner, it is obvious that these fittings are connected respectively to the condenser and compressor of the circulatory system with which my device is used. Such system does not form a part of this invention, and is, therefore, not described. It is to be noted, however, that one fitting is attached to one of the chambers and the other fitting is attached to the other chamber, and that the chambers are, therefore, connected 125 130

in series with each other. Furthermore, the device will also be in series with the compressor and condenser with which it is connected.

5 From the foregoing, it will be obvious that as suction is applied to the vapor fitting 46 connected to the chamber 11, a reduced pressure will be brought about or a pressure which is lower than the pressure at the so-called "high side" of the system. This will 10 increase the vaporization of the refrigerant, and tend to lower the level of the liquid refrigerant in the chambers as the vapor gas is drawn away. Since both chambers 10 and 15 20 are connected together, any lowering in the level of the refrigerant in the chambers will immediately be compensated for by the liquid flowing into the chamber 10 through the liquid control valve connected thereto. 25 The level of the liquid will, of course, be maintained constant in both chambers, and in doing so there will necessarily be a definite flow of the liquid refrigerant from chamber 10 to chamber 11, which will cause the lubricant 30 contained in the refrigerant to be carried along with it and to be thus kept in circulation. From the chamber 11 the lubricant is purged in any well known manner.

While I have shown but two adjacent cylinders with connections between them at the top for the passage of vapor and at the bottom for the passage of liquid refrigerant, it is obvious that more than two refrigerant chambers may be used if desired, the chambers would, of course, be connected near their upper and lower portions, and the liquid inlet fitting would be connected to one end chamber while the vapor outlet fitting would be connected to the other end chamber.

40 Obviously, these and other modifications of the details herein shown and described may be made without departing from the spirit of my invention or the scope of the appended claims, and I do not, therefore, 45 wish to be limited to the exact embodiment herein shown and described, the form shown being merely a preferred embodiment thereof.

Having thus described my invention, what 50 I claim is:

1. An evaporating unit for refrigerating apparatus, comprising a pair of adjacent, refrigerant chambers arranged in a substantially horizontal plane, and a compartment arranged below the chambers, the bodies of such chambers and the walls of the compartment being formed of a single sheet of material, the portions of such sheet which lie adjacent each other being formed with refrigerant passageways, and means for sealing the ends of the piece of material forming the body.

2. An evaporating unit for refrigerating apparatus, comprising a pair of adjacent, refrigerant chambers arranged in a substanti-

ally horizontal plane, and a compartment arranged below the chamber, the bodies of such chambers and the walls of the compartment being formed of a single sheet of material, the portions of such sheet which lie adjacent each other being formed with ridges providing refrigerant passageways, and means for sealing the ends of the piece of material forming the body.

3. An evaporating unit for refrigerating apparatus, comprising a pair of adjacent, refrigerant chambers arranged in a substantially horizontal plane, and an ice tray compartment arranged beneath the chambers, the bodies of the chambers and ice tray compartment being formed of a single piece of material formed with refrigerant passageways.

4. An evaporating unit for refrigerating apparatus, comprising a pair of adjacent, refrigerant chambers arranged in a substantially horizontal plane, an ice tray compartment arranged beneath the chambers, the bodies of the chambers and ice tray compartment being formed of a single piece of material, and ridges formed in the material, thus providing refrigerant passageways.

In testimony whereof I have hereunto signed my name.

EUGENE L. BARNES.
